COMBINED DICKEY AND BRA

Harry W. Froehlich, 1344 Marineie Road,
Pacific Palisades, Calif. 90272

Filed Apr. 12, 1974, Ser. No. 460,505

Term of patent 3½ years

Int. Cl. D2—02

U.S. Cl. D2—211

FIG. 1 is a front perspective view showing my new design for a combined dickey and bra;

FIG. 2 is a rear perspective of the same; and

FIG. 3 is a side view as seen from the left in FIG. 1.

I claim:

The ornamental design for a combined dickey and bra, as shown.
